UNITED STATES PATENT OFFICE.

CHARLES GUERITEY, OF PASSAIC, NEW JERSEY, ASSIGNOR TO PASSAIC METAL WARE CO., OF PASSAIC, NEW JERSEY, A CORPORATION OF NEW JERSEY.

CONVEYING MECHANISM.

Original application filed November 27, 1922, Serial No. 603,610. Divided and this application filed October 23, 1923. Serial No. 670,284.

This application is a division of my application for means for feeding can bodies, filed November 27, 1922, Serial No. 603,610.

The object of my invention is to automatically feed articles, such as can bodies or containers, to mechanism for securing covers upon such can bodies. The principal feature of my invention is to feed open ended can bodies or containers in a horizontal direction to devices for turning said can bodies upright with an open end uppermost, and to transfer such up-turned bodies to suitable mechanism for applying closures to the open ends thereof.

My invention comprises novel details of improvement and combinations of parts that will be more fully hereinafter set forth and then pointed out in the claim.

Reference is to be had to the accompanying drawings forming a part hereof, wherein

Fig. 1 is a side view of a feeding mechanism embodying my invention;

Fig. 2 is an end view looking from the left hand side of Fig. 1;

Fig. 3 is a detail section on line 3, 3, in Fig. 4;

Fig. 4 is a plan view;

Fig. 5 is an enlarged detail view illustrating means to actuate the can body trans-
ferrer;

Fig. 6 is an enlarged plan view, partly in section on the plane of line 6, 6, in Fig. 2;

Fig. 7 is a vertical section;

Fig. 8 is a detail perspective view of the can body transerrer;

Fig. 9 is a detail view, partly in section, showing seaming means;

Fig. 10 is a detail side view of the seaming device;

Fig. 11 is a plan of Fig. 10;

Fig. 11^a is a detail partly in section;

Fig. 12 is a plan view illustrating a modification;

Fig. 13 is a side view of part of Fig. 12, looking from the bottom of the latter figure;

Fig. 14 is a fragmentary detail;

Fig. 15 is an enlarged detail plan view.

Similar numerals of reference indicate corresponding parts in the several views.

Numeral 1 indicates the main frame of the machine which may be of any suitable construction, shown comprising horizontally disposed rails 2, provided with standards 3, 3^a at opposite ends. The frame at one

end is adapted to be attached to or located adjacent to frame 4 of a can seaming machine. Means are provided to feed containers, such as can bodies A, having either one or both ends open and disposed in a horizontal position to be fed to means for raising such can bodies to a vertical position with their open ends upwardly disposed, to be pushed into the seaming means to secure the closures B thereto. In Figs. 1 to 8 the body feeding means comprise an endless belt or conveyer 5 shown mounted between rollers 6, 7, 8, journaled upon the main frame. An idle pulley 9 carried upon a lever 10 pivoted at 11 upon the main frame, and operated by spring 12, serves to maintain desired tension in conveyor belt 5. At the sides of belt 5 are located spaced walls 2^a, supported by the rails 2, whereby the containers or can bodies are guided. Said conveyor belt may be driven continuously in any desired way. I have shown a driving shaft 13 having gear 14 in mesh with gear 15 secured on shaft 16 journaled in suitable bearings on the main frame, which shaft is provided with gear 17, in mesh with gear 18 on shaft 6^a of roller 6, whereby the conveyor belt 5 may be driven continuously. The can bodies A may be delivered to the conveyor to lie in a horizontal position thereon by any suitable means or manually. The conveyor is adapted to feed the can bodies to a transerrer 19 rotatively carried by shaft 20 journaled in suitable bearings on the main frame. The transerrer is adapted to be rotated to successively raise the can bodies delivered thereto from a horizontal to an upright position so that their open ends will be elevated into a position to receive closures or covers B to be seamed to the body. The transerrer 19 may be of any desired construction and is shown comprising spaced fingers having curved projections 19^b that are adapted to operate in spaced slots 21 in a plate 22 secured upon the main frame in substantial alignment with the upper run of conveyor 5 to receive the can bodies therefrom, (Figs. 7 and 8). The transerrer 19 is shown provided with stops 19^c to obstruct the can bodies as they are advanced to the transerrer by the conveyor. In the body receiving position the transerrer is located as indicated in Fig. 7 with its arms substantially within the slots

21 of plate 22, and the fingers 19^b below. When the transferrer is rotated to turn the can body to a vertical position, with its open end uppermost, the fingers 19^b will obstruct the advance of can bodies by the conveyor until said fingers are again lowered, (see Fig. 7). In the example illustrated the transferrer 19 is rotated back and forth for the purpose of alternately receiving the can bodies and turning them upwardly. For such purpose I have shown shaft 20 provided with a gear 23 in mesh with a rack 24 that is pivotally connected at 25 with a reciprocative rod 26 that is operated by a cam 27 secured on shaft 6^a. By preference, rod 26 is provided with resilient means to actuate the rack 24 for which purpose I have shown said rod made in two parts, 26^a, 26^b, having relative movement, and provided 20 with an interposed spring 28 (Fig. 6), shown coiled around rod part 26^a that is slidable in a bushing 29, carried by a cylinder 30 containing said spring, the rod part 26^a having a piston-like head or stop 31 between which head or stop and the bushing 29 the spring 28 is located. The rod part 26^b is shown secured by a nut or head 32 to cylinder 30 (see Fig. 6). Air in cylinder 30 between heads 31 and 32 aids rod part 30 26^b in pushing rod part 26^a to actuate the rack in one direction, the spring 28 actuating the rack in the other direction. A port 30^a in cylinder 30 permits flow of air into and from the cylinder. A spring 33, shown 35 coiled around rod part 26^a, bears against bushing 29 and against bearing 34 for rod part 26^a. The rod part 26^b is shown provided with a slotted head 35 slidable on shaft 6^a and provided with a projection 40 36 operative in the cam groove 27^a of cam 27, (Fig. 5). When said cam is rotated, the rack 24 will be reciprocated to rotate transferrer 19 back and forth, the springs 28 and 33 resiliently resisting operation 45 of the rack by cam 27, so that the transferrer will not injure the can bodies. When the transferrer 19 is rotated to raise a can body to vertical position, the latter is brought to rest at its side against a wall or stop 37 (Fig. 7). Said wall or stop 37 may be adjusted with respect to the transferrer by means of slots 37^a in the base of the wall and screws 38 shown passing through said slots and secured to the main frame part 3^a, (Figs. 6 and 7).

When a can body is presented on end with its open end upwardly disposed it will be in position to be transferred to any suitable place, such as to seaming mechanism to secure the closure or head B to the body. In 50 the example illustrated, I have shown a turret 39 that is carried by a shaft 40 journaled in the frame 4, which turret may be rotated step-by-step by any well known mechanism utilized in can seaming machines. The tur- 55 ret is shown provided with spaced receivers or pockets 41, radially disposed and having their outer sides open to receive the can bodies which rest on the platform 39^a. I provide means to push the can bodies from the transferrer into the turret. In the example illustrated, the pusher or plunger 42 is located in register with a pocket 41 of the turret and is shown comprising a suitable head upon a reciprocative rod 43 guided by bearing 44, supported by the frame part 3^a and adapted to be reciprocated to push the can bodies from the transferrer into the pockets of the turret. Any suitable means may be provided for reciprocating pusher or plunger 42. I have shown a forked arm 45 pivotally supported on shaft 46, journaled in bearings on the main frame, the forks of which arm receive lateral projections 47 extending from rod 43. The shaft 46 is shown provided with a crank arm 48 pivotally connected with a block 49 slidable on a rod 50. The rod 50 has a stop 51 against which a spring 52 bears, said spring also bearing against block 49, the latter being retained by nut 53 on rod 50, whereby said rod may resiliently push the block 49 to operate the pusher or plunger 42. The rod 50 is pivotally connected at 54 with a crank arm 55 shown pivotally supported at 56 on the main frame, which crank arm is shown provided with a projection 57 cooperative with a cam 58 on shaft 16. Cam 58 is timed to cause operation of pusher or plunger 42 through the parts 55, 50, 48, 46 and 45 so that when a can body has been presented by transferrer 19 in position in register with a receiver or pocket 41 of the turret said pusher will push the can body into said receiver, and will recede from the transferrer which will operate to receive another can body and present it in register with a receiver of the turret just after the pusher has been retracted from relation to the transferrer. 100

When a can body has been pushed by pusher 42 from the transferrer into a receiver of the turret, the closure B for the open end of the can body will be placed on said body. The closures B may be of suitable form to be seamed to the edges of the can bodies at their open ends, which closures may be retained stacked in a magazine or support 59 of any suitable or well known character, (Fig. 2), from which the closures may be fed upon the successive can bodies in the turret by hand operation, or by any suitable or well known means adapted for the purpose. When a can body with its closure B laid thereon has been carried 105 around by the turret to a suitable position, it will be brought to rest respecting seaming devices of any suitable or well known character, not forming a part of my present invention as to structure. I have illustrated 110

120

125

130

spaced seaming rolls 60 supported over a suitable part of the turret and driven by intermeshing gears 61 carried by shafts 62, which parts may be supported and rotated in any desired manner to cause the seaming rolls to act upon the edges of the closure and the can body to seam them together, as indicated in Fig. 9. Any suitable means may be provided for elevating the can bodies 10 with their closures to the seaming tools, such as by means of a reciprocative lifter indicated at 63 adapted to be operated by a reciprocative rod 64 to be actuated in any suitable way to raise and lower the can bodies 15 when the turret comes to rest, (Fig. 2). The seaming devices and lifter 63, which form part of the seaming mechanism, will be caused to operate in relation to the step-by-step movements of the turret to cause seaming 20 of the closure to the can body at each stop of the turret.

After the closures have been seamed to the can bodies, the latter may be ejected from the turret by any suitable means and 25 may be received upon a conveyor to carry them away, or may be delivered in any other suitable manner. Guards 65 are shown arranged around the turret and at the delivery point of wall 66 which obstructs the can 30 bodies, (Fig. 6). Where closures are to be applied to both ends of the same can, they may be delivered to a conveyor 5^a, supported similarly to the conveyor 5, one roller for the conveyor 5^a being indicated at 6^b, (Figs. 1, 35 6 and 7). The conveyor 5^a may be operated in consonance with the conveyor 5 by means of a sprocket chain 67 operating upon a sprocket wheel 68 on shaft 6^a of roller 6^b and upon a sprocket wheel 69 on the shaft 8^a of 40 roller 8. When the can bodies or containers having the closures or heads secured at one end are delivered upon conveyor 5^a, they will be turned on their sides so that their then open ends extend rearwardly and will 45 be fed by said conveyor successively to a second transfeerer associated with a second turret and seaming devices of the character herein described, which transfeerer will operate to turn such can bodies upwardly, 50 with their open ends uppermost, and their previously closed ends downwardly disposed, in position to be pushed by a corresponding pusher 42 into the associate turret, upon which open ends of can bodies the closures 55 or bottoms B will be placed and seamed to the can bodies in manner before described. The arrangement described enables the continuous operation of containers or can bodies to have their closures or heads applied and seamed at opposite ends without any manual handling being required from the time they are first placed upon conveyor 5.

Instead of using a belt-like conveyor to 60 feed the bodies or containers A to the trans-

ferrer, the bodies may be fed successively in any other desired way. In Figs. 12 to 15 a reciprocative bar 70 is suitably guided along the rails 2 and is shown provided with spring pressed dogs 71 pivoted on bar 70 at 72 and controlled by springs 73, (Fig. 14). The dogs 71 project through a slot 74 longitudinally disposed in a guiding plate 75 supported by rails 2 and on which can bodies or containers may slide. The dogs 71 75 serve to push the bodies to transfeerer 19. A rail 76 supported above bar 70 is provided with back stops 77 pivoted to rail 76 and depending into the path of the bodies A to 80 resist backward thrust of the latter when the dogs 71 slide reversely under the can bodies. Stops 78 on rails 76 limit upward thrust of the back stops 77. The can bodies or containers slide upon the plate 75 between the spaced walls 2^a whereby the bodies are guided to the transfeerer. The bar 70 may be reciprocated in any desired way, such as by means of link 79 pivotally connected with said bar and pivotally connected with a rock lever 80 that is pivotally supported at 81 on bracket 82, said lever being pivotally connected to a link 83 that is pivotally connected at 84 with a crank 85 on a shaft 86 supported by the main frame. Shaft 86 may be rotated by chain and sprocket 87, 88 or in any other desired way in relation to the step-by-step rotation or rocking of transfeerer 19.

In Figs. 12, 13 and 15 modified forms of means for reciprocating pusher or plunger 43 are shown as follows: The rod 50 that extends from lever 45 is pivotally connected with horizontally disposed crank arm 55 pivoted at 56 and actuated by projection 57 and cam 58 on shaft 58^a to be rotated in any suitable way.

In accordance with my invention, the can bodies or containers, having one or both ends open, may be delivered in any suitable way to the conveyor to lie thereon in a horizontal 110 position with the open ends that are to be provided with closures extending rearwardly respecting the transfeerer. An advantage is that the can bodies may be fed directly from a can body forming machine as 115 they are produced, without requiring intermediate handling. The conveyor will feed the can bodies to the transfeerer either successively and continuously by means of the conveyor belt 5, or successively and step-by-step by the reciprocative bar 70. In either case, when the transfeerer is in body receiving position the pusher or plunger 42 will be at one side thereof and the transfeerer will be operated to raise the can body thereon from a horizontal position to an upward position in front of the pusher, with an open end of the can uppermost in register with the turret. When the transfeerer comes to 120 rest with a can body in the last named posi-

tion, the pusher will operate to push the can body into a receiver of the turret and the pusher will retreat so that another can body may be placed by the conveyor upon the 5 transferrer. In the example illustrated, the transferrer will be located in a position to receive another can body or container, to be turned to an upright position, and so on for each body or container to be provided with 10 a closure. When a can body or container has been placed in a receiver or pocket of the turret, a closure B will be placed on the open end of the can body and the turret will rotate a step for each can body. After the 15 can bodies or containers with closures thereon are carried around by the turret to the seaming mechanism the can bodies will be presented in position to have their closures seamed to the bodies by the seaming mechanism, after which the headed can bodies will be discharged from the turret successively to any desired receiver, as upon the conveyor 20 5^a. Heretofore, so far as I am aware, can bodies have been fed to seaming mechanism 25 either manually or by chutes for standing the can bodies on end upon a conveyor that would feed such bodies to the seaming mechanism. Where small can bodies, and those having irregular shapes, such as oblong in 30 cross section, are placed upon a conveyor they are liable to be tilted out of position with the result that they are not always fed properly to the seaming mechanism or the turret thereof, necessitating manual attention to the 35 feeding of the bodies to the seaming mechanism. By means of my invention the objection to feeding can bodies or containers to a conveyor standing on end with their open

ends extending upwardly is overcome, since the can bodies may lie on their sides until 40 they are turned on end in position conveniently to be pushed to the seaming mechanism or the turret thereof, thereby overcoming danger that the can bodies will be inaccurately or irregularly fed to the seaming mechanism, whereby the operations are 45 expedited and loss of can bodies or containers by improper feeding is minimized.

While I have illustrated a transferrer for 50 the can bodies that is adapted to be rotated or rocked back and forth to receive the can bodies and turn them on end in position to be pushed to the seaming mechanism, it is to be understood that my invention is not limited to the particular construction for back and 55 forth operation of the transferrer, since the same could rotate continuously in one direction, and that changes may be made in the details of construction set forth, within the scope of the appended claim, without departing 60 from the spirit of my invention.

Having now described my invention, what I claim is:

The combination of means to feed containers successively, a transferrer having 65 means to receive said containers, a shaft carrying said transferrer, a gear upon the shaft, a rack to operate the gear, a reciprocative rod to operate the rack, said rod having a plurality of members and interposed resilient 70 means to cushion the thrusts of the rod, means to reciprocate the rod, means to push containers from the transferrer, and seaming mechanism comprising a turret provided with receivers for the containers.

CHARLES GUERITEY.
